United States Patent Office

Des. 196,361
Patented Sept. 24, 1963

196,361

TRUCK

Don W. Cartner, Kansas City, Mo., assignor to Pasley
Mfg. & Distributing Co., Kansas City, Mo., a corporation of Missouri

Filed Dec. 26, 1962, Ser. No. 72,956

Term of patent 14 years

(Cl. D14—3)

Fig. 1.

Fig. 2.

Fig. 3.

Fig. 4.

Fig. 5.

FIG. 1 is a rear perspective view of a truck, showing my new design;

FIG. 2 is a rear elevational view thereof;

FIG. 3 is a front elevational view thereof;

FIG. 4 is a top plan view thereof; and

FIG. 5 is a side elevational view of the left side of a truck.

The dominant features of my design reside in the portions shown in full lines.

I claim:

The ornamental design for a truck, as shown and described.
